[57] **CLAIM**

The ornamental design for a combined key ring and clip
lock for holding a gas pump trigger in the open position,
as shown.

DESCRIPTION

FIG. 1 is a perspective view of a combined key ring and
clip lock for holding a gas pump trigger in the open
position showing my new design;

FIG. 2 is a side elevational view thereof;

FIG. 3 is an end elevational view taken from the left of
FIG. 2;

FIG. 4 is an end elevational view taken from the right of
FIG. 2;

FIG. 5 is a top plan view thereof;

FIG. 6 is a bottom plan view thereof.
